Louis Staub, George Rittoff, and Harry M.
Gresen, New York, N. Y.

Application September 16, 1944, Serial No. 115,324

Term of patent 14 years

(Cl. D34—13)

To all whom it may concern:

Be it known that we, Louis Staub, George Rittoff, and Harry M. Gresen, all citizens of the United States, all residing at New York, New York, in the counties of New York, New York and Bronx, respectively, and all in the State of New York, have invented a new, original, and ornamental Design for a Set of Playing Cards, of which the following is a specification, reference being had to the accompanying drawing, forming a part thereof.

In the drawing:

Fig. 1 is a top plan view of a set of playing cards, showing our new design.

Fig. 2 is a rear face view of each card shown on Fig. 1.

We claim:

The ornamental design for a set of playing cards, as shown.

LOUIS STAUB.
GEORGE RITTOFF.
HARRY M. GRESEN.
